CAN OPENER

Winfield J. Starr, Philadelphia, Pa.

Application September 24, 1958, Serial No. 762,977

7 Claims. (Cl. 30—8.5)

This invention relates generally to can openers, and is especially concerned with a highly improved construction of can opener adapted to effect severance of the can end by approximately axial rotation of the can in engagement with a cutting element.

It is one object of the present invention to provide a can opener of the type described which is more durable in construction and reliable in operation, having an extremely long usable life and consistently effecting clean and complete severance of cans being opened.

It is another object of the present invention to provide a can opener having the advantageous characteristics mentioned in the preceding paragraph which is extremely simply in structure and very easy to operate, effecting more than ample cutting force with a minimum of effort.

It is still a further object of the present invention to provide a can opener of the character described which is capable of being produced either as an externally supported device, say as a wall-mounted can opener, or as a hand-held device, as desired by the manufacturer.

Other objects of the present invention will become apparent upon reading the following specification and referring to the accompanying drawings, which form a material part of this disclosure.

The invention accordingly consists in the features of construction, combinations of elements, and arrangements of parts, which will be exemplified in the construction hereinafter described, and of which the scope will be indicated by the appended claims.

In the drawings:

Figure 1 is a side elevational view showing a hand-held type of can opener constructed in accordance with the teachings of the present invention;

Figure 2 is an end elevational view showing the can opener of Figure 1;

Figure 3 is a partial elevational view taken from the opposite side as is Figure 1;

Figure 4 is a partial top plan view of the device of Figures 1-3;

Figure 5 is a sectional view taken substantially along the line 5—5 of Figure 2 and showing the device in its inoperative condition in solid lines, the operative condition being illustrated in dot-and-dash outline;

Figure 6 is a sectional view taken substantially along the line 6—6 of Figure 5;

Figure 7 is a sectional view similar to Figure 6, but showing the operative condition of use;

Figure 8 is a side elevational view showing a slightly modified can opener of the present invention adapted to be mounted on a supporting wall;

Figure 9 is a sectional elevational view showing the interior construction of the can opener of Figure 8;

Figure 10 is a partial top view taken substantially along the line 10—10 of Figure 8;

Figure 11 is a sectional elevational view taken substantially along the line 11—11 of Figure 10; and

Figure 12 is a bottom view taken substantially along the line 12—12 of Figure 11.

2

Referring now more particularly to the drawings, and specifically to Figures 1-7 thereof, a hand-held can opener may be observed as generally designated 20 in Figure 1, and includes broadly a handle 21 and an operating head 22. A generally flat, elongate underplate or base 23 rigidly connects and forms part of both the handle and head. The base plate 23 includes an elongate portion 24 which fixedly carries on its upper side a hand-grip 25, combining with the latter to define the handle 21.

10 Extending from one end of the elongate handle portion 24 of the base 23 is a laterally enlarged end region 26, which has its laterally extending region defining an arcuately concave edge 27, see Figure 4, for seating a can as will become apparent presently, and which rigidly carries on its upper side a generally vertical body 28, the base portion 26 and body 28 both being parts of the head 22.

The body 28 may be of vertically elongate, generally rectangular hexagonal configuration having its lower end fixed to the upper surface of the base portion 26, and provided on its upper end with an upstanding, internally threaded tubular boss 29. Formed interiorly of the body 28 in an upper region thereof is a through slot or hollow 30 opening through opposite surfaces of the body longitudinally of the base 23 and spaced above the latter. An additional hollow or recess is formed internally of the body 28 extending downward from the hollow 30 at 31, adjacent to and opening through the outer side of the body longitudinally of the base, and further extending

25 downward at 32 to the base end region 26. More specifically, the internal hollow region 31 extends downward and converges forwardly from the upper internal hollow region 30 to the lower internal hollow region 32, the intermediate and lower hollow regions 31 and 32 being spaced from the rearward surface of the upstanding body 28 and opening through the forward surface thereof. This is best seen in Figure 5, where it is also evident that the hollow regions 30, 31, and 32 combine to define in the body 28 a member 33 in the lower rearward region

30 of the body having a generally horizontal upper surface region 34 bounding the upper hollow region 30, and a diagonally extending, forwardly and upwardly facing surface region 35 bounding the hollow region 31, and a forwardly facing surface 36 bounding the lower internal hollow region 32. As is apparent from the drawings, the surface region 34 extends forwardly from the rearward surface of the body 28, the surface region 35 extending forwardly and downwardly from the forward end of the surface region 34, and the surface region 36 extending downwardly from the lower forward end of the surface region 35, terminating at the base region 26.

40 Formed in opposite sides of the body 28, above the internal body member 33, are a pair of aligned, vertically extending, through slots 40. That is, the slots 40 each extend laterally inward through a respective side of the body 28, opening into the hollow 30, and are in substantial alignment or registry with each other. In addition, the slots are in substantial vertical alignment with the upstanding tubular boss 29.

45 Defining an internal downward extension of the interior of boss 29, in the hollow 30, is a bore 41 having complementary recesses formed in opposite internal sides of the hollow 30. The bore 41 is in substantial vertical alignment with the slots 40, and terminates at its lower end adjacent to and above the slots.

50 A lever 45 includes a pair of arms 46 and 47 rigidly connected together in generally right-angular relation, with the distal end region 48 of the arm 46 located in the hollow 30 and the distal end region 49 of the arm 47 located exteriorly of the body 28. The arm end region 48 is mounted interiorly of the body 28 on a pivot pin or journal 50 extending laterally across the hollow

30 and having spaced regions slidably and rotatably received in respective slots 40 of the body 28. Thus, the lever end region 48 is mounted by the pin 50 for rotation about the axis of the latter, and also for translation or shifting movement in the vertical direction within the limits of the slots 40. Rigidly or integrally carried by the lever end region 48 internally of the hollow 30 is an enlargement or cam 53, which may be of generally circular configuration and arranged eccentric with respect to the pin 50. It will be noted that the arm 46 has its distal end region offset with respect to its inner end region and with respect to the central region of the cam 53.

As seen in Figure 5, in solid lines, with the lever 45 swung to its extreme clockwise position and the edge or edge surface of cam 53 engaging the member or guide 33, and particularly the surface region 34 thereof, the pin 50 is in its uppermost position in the slots 40. Further, with the lever 45 in its extreme position of counterclockwise movement, shown dot-and-dash outline, and the edge of cam 53 engaging guide member 33 just at or slightly forward of the intersection of surface regions 34 and 35, the pin 50 is in its lowermost position of vertical movement in the slots 40.

In order to yieldably maintain the cam 53 with its edge in bearing engagement with the upwardly facing surface regions of guide member 33, an externally threaded plug 55 is engaged in the boss 29, and has a spring 56 depending through the boss 29 into the bore 41 and carrying on its lower end a button or retaining element 57 in engagement with the edge surface of cam 53 generally opposite to the region of cam engagement with the guide member 33. As may be observed in Figure 5, the location of retaining head 57 in engagement with the cam 53 cooperates with the location of cam engagement with the guide-member bearing surfaces 34 and 35 to yieldably retain the cam in both of the illustrated positions.

Slidably engaged astride the body 28 is a yokelike carrier 60 having an apertured upper, medial region 61 spacedly receiving the boss 29, and depending extensions or legs 62 and 63 on opposite sides of the head 28. The pin 50 has its opposite end portions projecting through and secured to respective legs 62 and 63 of the carrier 60, so that the latter is vertically slidable with the pin upon vertical shifting movement of the latter and limited by pin engagement with opposite ends of the slots 40. Spaced below the ends of pin 50 secured to the legs 62 and 63, the latter are respectively formed with vertically elongate slots 64 and 65. Located intermediate the slot 64 and the pin 50, exteriorly on the leg 62 of carrier 60, is a mounting block 66 to which is fixed a depending cutter 67 having an obliquely extending knife edge 68.

A laterally extending shaft 70 is journaled in the lower region of the body 28, extending laterally therebeyond through the slots 64 and 65 of the carrier legs, and carrying on one end, adjacent to the cutter 67, a toothed feeding wheel 71. That is, the toothed feeding wheel 71 is located directly beneath the mounting block 66, so that the cutter 67 is movable relative to the feeding wheel between the inoperative position of Figure 6 and the operative position of Figure 7. On the other end of rotary shaft 70 is fixed a crank arm or turning handle 72 for manually effecting rotation of the feeding wheel 71.

In operation, the handle 21 may be grasped in one hand of the operator, and the lever 45 swung upward, the position illustrated in Figures 1-4. The can opener 20 is then arranged to engage the bead of a can over the feeding wheel 71, beneath the mounting block 66 and cutter 67. The lever 45 is then swung downward to the position illustrated in dot-and-dash outline in Figure 5, and also shown in Figure 7, whereupon the cutter 67 punctures the can and initiates cutting action. The side wall of the can is seated against the edge 27 of the base portion 26, and the upper end bead or chine of the can

5 is retained between the feeding wheel 71 and mounting block 66. Hence, upon rotation of the feeding wheel, as by actuation of the crank arm 72, the can is axially rotated while being held in position to be cut by the cutter 67.

10 In the embodiment of Figures 8-12 are shown a can opener similar to that of Figures 1-7, but wherein the device is modified for permanent mounting on a wall or other suitable supporting surface. The can opener of Figures 8-12 is generally designated 20a and is mounted on a wall surface 37. The can opener includes an arm 21a corresponding and similar to the handle 21, and a head 22a corresponding and similar to the head 22. By way of difference, the arm 21a is provided on its end remote from the head 22a with a structure 75 for mounting the device on the wall surface 37; and, the head 22a has been reversed, or turned 180° about a vertical axis with respect to the base plate 23a to facilitate right-hand manual operation from the front of the device, rather than from the rear.

15 To further facilitate operation from the front, the lever 45a, corresponding to the lever 45, swings between the generally horizontal position of Figure 9, and a depending position (not shown), the base end region 26a being provided with a cutout 76 for receiving the lever in its depending position. Of course, the principles of operation of the embodiments are substantially identical.

20 The mounting structure 75 includes a bracket 77 having a generally vertical plate 78 adapted to be fixed to the wall surface 37, as by fasteners 79. A pair of vertically spaced, generally horizontal lower and upper plates 80 and 81 project outward from the wall plate 78; and, a generally vertically disposed journal pin or bolt extends between and through the horizontal plates 80 and 81, as best seen in Figure 11. The journal pin 82 may be a conventional square-headed bolt, having its head 83 on the underside of the lower plate 80, and having its threaded-end region projecting in spaced relation through and upward beyond the upper plate 81. The end region 85 of the arm 21a remote from the head 22a is provided with a generally vertically disposed through bore 86 through which extends the pin 82 for mounting the can opener 20a for rotation about the axis of the bolt.

25 A boss or enlargement 87 is provided on the underside of lower plate 80 and configured for engagement with one flat side of the bolthead 83 to prevent axial rotation of the bolt. Formed in the lower plate 80 spaced angularly about the axis of bolt 82 are a plurality of through apertures 88; and, a depending projection 89 is formed on the underside of the arm 21a for engagement in a selected one of the apertures 88. As the bracket plates 80 and 81 are spaced apart vertically a greater distance than the vertical dimension of the arm 21a, the arm is vertically shiftable along the bolt 82 between the bracket plates. Thus, the projection 89 is removably insertable into a selected one of the apertures 88, and upon removal from one such aperture, the arm 21a may be rotated about the bolt 82 to the desired angular position, and lowered to engage the projection in another of the apertures. Slidably circumscribed about the bolt 82, and received in the upper bracket plate 81 when seated on the upper side of the arm 21a, is a tubular member or spacer 84. A nut 90 is threadedly engaged on the upper end of the bolt 82 above the spacer 84 and is movable downward into engagement with the spacer to prevent upward shifting movement of the arm 21a, and therefore prevent withdrawal of projection 89 from its receiving aperture 88, and consequently rotation of the arm about the bolt. However, when it is desired to effect arm rotation, the nut 90 may be raised on the bolt 82, thereby permitting elevation of the arm 21a to disengage the projection 89 from its receiving aperture 88 for free rotation of the arm.

30 From the foregoing, it is seen that the present inven-

tion provides a can-opener construction which fully accomplishes its intended objects and is well adapted to meet practical conditions of manufacture and use.

Although the present invention has been described in some detail by way of illustration and example for purposes of clarity of understanding, it is understood that certain changes and modifications may be made within the spirit of the invention and scope of the appended claims.

What is claimed is:

1. A can opener comprising an upstanding hollow body, a cam guide in said body having an upwardly facing cam bearing surface, a lever having one end interiorly of said body above said bearing surface and having its other end extending exteriorly of said body, pivot means mounting said one lever end for rotation about an axis transverse of said body and translatory movement toward and away from said bearing surface, a cam fixed to said one lever end for movement therewith and engagement with said bearing surface, resilient means in said body above said cam and engaging with the latter to maintain said cam against said bearing surface, said cam being configured for coacting engagement with said bearing surface to effect lever translation in opposite directions upon lever rotation in opposite directions respectively, a can-feeding wheel disposed exteriorly of and rotatably carried by said body, a cutter mounted on said body for shifting movement toward said feeding wheel into operative relation with the latter and away from said feeding wheel out of said operative relation, and means operatively connecting said cutter to said lever for effecting cutter shifting movement into and out of said operative relation upon lever translation in opposite directions.

2. A can opener according to claim 1, in combination with an arm extending transversely from said body and carrying the latter.

3. A can opener according to claim 2, said connecting means comprising a carrier slidably engaged on said body and connected to said pivot means for translatory movement therewith, said cutter being carried by said carrier for movement therewith.

4. A can opener according to claim 3, said connecting means further comprising a mounting member fixedly secured to said carrier and cutter for carrying the latter with said carrier, said mounting member having

one side facing toward the periphery of said feeding wheel generally normal to a radius thereof and engageable with the chine of a can to maintain the latter in proper position relative to the feeding wheel and cutter.

5. A can opener comprising an upstanding hollow body, a cam guide in said body having an upwardly facing cam bearing surface, a lever having one end interiorly of said body above said bearing surface and having its other end extending exteriorly of said body, pivot means mounting said one lever end for rotation about an axis transverse of said body and translatory movement toward and away from said bearing surface, a cam fixed to said one lever end for movement therewith and engagement with said bearing surface, resilient means in said body above said cam and engaging with the latter to maintain said cam against said bearing surface, said cam being configured on one side for coacting engagement with said bearing surface to effect lever translation in opposite directions upon lever rotation in opposite directions respectively, said cam being configured on its other side for engagement with said resilient means to be releasably retained by the latter in a selected position of its movement, a can-feeding wheel disposed exteriorly of and rotatably carried by said body, a cutter mounted on said body for shifting movement toward said feeding wheel into operative relation with the latter and away from said feeding wheel out of said operative relation, and means operatively connecting said cutter to said lever for effecting cutter shifting movement into and out of said operative relation upon lever translation in opposite directions.

6. A can opener according to claim 5, in combination with means for adjusting the force of said resilient means to assure of maintenance of said cam against said bearing surface.

7. A can opener according to claim 6, said resilient means comprising a coil compression spring in said body having one end in operative bearing relation with said other side of said cam, and said adjustment means comprising a threaded member threadedly engaged in said body and in operative bearing relation with the other end of said coil compression spring.
